CLAIM

I claim the ornamental design for a protective cover, as shown and described.

DESCRIPTION

FIG. 1 is a perspective view of a protective cover;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a reference perspective view showing the protective cover in use; and,
FIG. 9 is another reference perspective view showing the protective cover in use.
The broken lines represent portions of the protective cover that form no part of the claim.
